[57] ABSTRACT

A safety step bar, e.g. for use in the manufacture of ladders, includes a first longitudinally extending strip and a second longitudinally extending strip which are disposed in parallel relationship and spaced by a plurality of transversely extending bars between the inner surfaces of the first and second strips. The upper edges of the longitudinally extending strips are formed to define prongs for providing a non-skid surface for the step bar.

The bar of the invention is disclosed as being manufactured by extrusion or like processes to define a monolithic structure to improve the manufacturing economies.

SELF CLEANING SAFETY STEP BAR

BACKGROUND OF THE DISCLOSURE

This invention relates to the field of structural shapes. More specifically, this invention relates to structural bars useful for the manufacture of steps for ladder structures.

Self cleaning safety step bars are generally known in the ladder construction art. It is known in the ladder manufacturing arts to provide step bars which have an abrasive or other non-friction surface as well as a plurality of vertically extending openings which accommodate the disposition of dirt which may be deposited upon the step bars from the feet of users.

Typical of the step bars generally known in the arts is that which may comprise first and second longitudinally extending strips which are separated by a generally longitudinally extending sinuous strip. The upper surfaces of the respective strips are provided with a non-skid surface or upwardly extending prongs and the sinuous strip cooperates with the longitudinally extending strips to define the vertically extending openings through which dirt scraped from the shoes of a climber can pass to maintain the ladder in a relatively clean condition.

Although step bar structure of the type described above has been very well accepted in the industry, it has been recognized by those skilled in these arts as being relatively expensive to manufacture. Specifically, the structure of the average metal ladder utilized in the industry today includes a pair of parallel ladder rails between which extends a plurality of longitudinally spaced step bars or rungs. Where such step bars are of the self cleaning type, manufacturing difficulties have been experienced in two areas. Initially, the fabrication of the step bars has been a source of difficulty and secondly the securing of the step bars to the ladder rails has also caused problems.

Considering initially the fabrication problems which have been experienced, the prior art manufacture of self cleaning step bars has required the positioning of spaced longitudinally extending strips in special jigs. Thereafter, the strips are joined with spacer means by such procedures as welding, riveting or the like. It is considered to be clear that avoiding the use of such special jigs and the accomplishing of plural securing steps would be definite improvements in the art of manufacturing safety step bars.

Considering secondly the problem relating to the securing of step bars to ladder rails, it will be understood by those skilled in this art that the manufacture of ladders using known step bars has required the fitting of the outer step strips as well as an individual fitting of the spacer section at each point of connection between the step bar and the ladder rails. Often such manufacturing steps require a plurality of cuts on each end of the step bar structure and once cut, the step bar must be secured to the ladder rails by welding three elements of the bar to the ladder rail, one of the welds being a difficult inner section weld.

SUMMARY OF THE INVENTION

It is an object of the present invention, therefore, to provide a structural bar capable of use as a self cleaning step bar, which is inexpensive to manufacture and structurally sound.

A further object of the present invention is to provide a self cleaning safety step bar which is non-skid and which provides no source for the deposit of dirt and other materials during use.

Still another object of the present invention is to provide a safety step bar configuration wherein manufacture of ladders therewith is rendered more easy and more economical.

These objects and others not enumerated are 10 achieved by the self cleaning safety step bar according to the invention one embodiment of which may include first and second spaced elongated strips extending longitudinally, a plurality of longitudinally spaced transversely extending spacer bars disposed between said 15 first and second strips, and a plurality of prongs formed on the surfaces of said first and second elongated strips to provide a source of friction.

BRIEF DESCRIPTION OF THE DRAWINGS

20 A more complete understanding of the present invention may be had in the light of the following detailed description thereof, particularly when read in the light of the accompanying drawings wherein:

25 FIG. 1 is a plan view, partly in cross-section of a ladder structured in accordance with the prior art teachings regarding typical self cleaning safety step bars;

FIG. 2 is a view similar to FIG. 1 but showing a ladder utilizing a self cleaning safety step bar according to the invention;

30 FIG. 3 is a perspective view of a self cleaning safety step bar according to the invention;

FIG. 4 is a plan view of a safety step bar according to the invention; and

FIG. 5 is a cross-sectional view through the plane 35 5-5 of FIG. 4.

DETAILED DESCRIPTION

The problems to which the present invention are directed may be best understood by referring to FIG. 1 40 wherein a ladder utilizing self cleaning safety step bar structure is shown. Specifically, prior art ladder 10 is seen to comprise first and second ladder rails 11 and 12, respectively. Rails 11 and 12 extend longitudinally in parallel spaced relation and are separated by a plurality of step bars or rungs 14 in a conventional manner.

The prior art step bar 14 comprises first and second 45 longitudinally extending strips 16 and 17 which are separated by a generally longitudinally extending sinuous spacer member 18. Each of the longitudinally extending strips and the spacer member are provided with perforations along their upper surfaces to provide a non-skid surface. Further, the vertically extending spaces defined by the cooperation of the longitudinally extending strips and the continuous member provides for the self cleaning aspect in that dirt scraped from the shoes of a climber will drop down between the strips and the spacer and not be built up on the surface of the ladder step bar so as to generate a possibility of slipperiness or other unsafe condition.

The structural difficulties attendant to ladders structured in accordance with the prior art as disclosed in FIG. 1 are reasonably evident. Specifically, the manufacture of the self cleaning safety step requires that the continuous spacer bar be joined to the longitudinally extending strips at a plurality of points 19 along the length of the bar structure. This of course, requires a

number of welds and increases the cost of manufacture. Secondly, it can be seen that at the point of juncture between the step bar and the ladder rails there is required a tailored fitting of the step bar to the rail. Specifically, each of the longitudinally extending strips must be cut and then the continuous strip must be cut such as to define a three point surface which fits the circular cross section of the ladder rail. This, of course, requires a special cutting in each individual case and renders manufacture of a ladder in this manner very difficult. Further, once the step bar is cut, securing of the step bar to the ladder rail requires welding at three points. All of this is expensive and disadvantageous.

The self cleaning step bar according to the present invention is advantageous because of the ease of its own manufacture, however it is also advantageous because of the manner in which it facilitates the manufacture of ladder structure and avoids the prior art difficulties as outlined above. Accordingly, referring to FIG. 2, a ladder utilizing a safety step bar according to the present invention is designated generally by the reference numeral 20. Ladder 20 is seen to comprise first and second ladder rails 22 and 24 each of which being generally cylindrical in cross sectional configuration. Rails 22 and 24 extend longitudinally in parallel spaced relation and are separated by a plurality of safety step bars according to the present invention, which bars are designated generally by the reference numeral 26.

Safety step bar 26 is a generally U-shaped member having a first longitudinally extending strip 28 and a second longitudinally extending strip 29 disposed parallel to the first strip. Each longitudinally extending strip includes an upper surface, a lower surface, an inner surface and an outer surface, the outer surface of each having a shoulder formed thereon to define a longitudinally extending portion of increased thickness adjacent the upper surface. The first and second longitudinally extending strips are spaced by a plurality of transversely spaced bars 31 extending between the inner surfaces of first and second strips 28 and 29, the detailed structure of which is discussed below. As is also discussed below in detail, a plurality of upwardly extending prongs 33 are formed in the increased thickness portions of first and second longitudinally extending strips 28 and 29 so as to provide a non-skid surface for step bar 20.

As is evident from FIG. 2, step bar 20 is joined to first and second ladder rails 22 and 24 by welds 35. In this regard, it is to be noted that because of the absence of a generally longitudinally extending spacer member such as that 18 of the prior art embodiment of FIG. 1, there is no need for special cutting or shaping of a spacer element between a longitudinally extending strips 28 and 29. Thus, in manufacturing a ladder 20, it is satisfactory to cut a long strip of safety step bar into sections to form a plurality of safety step bar rungs 26 position first and second ladder rails 22 and 24 in parallel spaced relationship position the rungs 26 appropriately along the length of the ladder between first and second ladder rails 22 and 24 and thereafter join the ladder rails and step bars such as by welding 35. Thus, in manufacturing a ladder such as ladder 20, there is no need for custom fitting of the step bars to the ladder rails, rather the step bars can merely be cut, positioned against the rails and appropriately welded.

Considering now the detailed construction of step bars according to the invention and with particular ref-

erence to FIGS. 3, 4 and 5, step bar 20 can be seen to be a generally U-shaped structure comprising first longitudinally extending strip 28, second longitudinally extending strip 29 and a plurality of transversely extending spacer bars 31. In the embodiment shown, the upper edges of first and second longitudinally extending strips 28 and 29 are increased in thickness such as to form shoulders on the outer surfaces of each strip. These thickened sections are provided to accommodate the forming of a plurality of friction-generating prongs 33 on the upper edges of strips 28 and 29 in a manner discussed below in detail.

As may be best seen in FIG. 4, spaced transverse bars 31 cooperate to define openings 37 between first and second longitudinally extending strips 28 and 29. These openings are to accommodate the passage therethrough of dirt and like materials which may be scraped from the feet of a user of a ladder structured in accordance with the invention.

Considering now the manufacture of a safety step bar according to the invention, the preferred method of manufacture is to extrude a generally U-shaped bar having a cross sectional configuration as shown in FIG. 5. Such an extrusion can be made by any of the methods of extrusion for accomplishing the manufacture of such a product as is generally known by those skilled in the extrusion arts. With the basic extrusion shape formed, prongs 33 are formed by punching. More specifically, the upper edges of longitudinally extending strips 28 and 29 are passed through a punching apparatus which punches the upper edges to form relieved portions 37, which in the embodiment shown are semi-circular, thereby leaving prongs 33 which extend upwardly from the surface of strips 28 and 29.

After the relieved portions 38 are formed in strips 28 and 29 to form prongs 33, bar 26 is passed through a stamping machine wherein the base portion of U-shaped bar 26 is stamped to define openings 37 thereby forming transversely extending spacer bars 31. Such stamping is the final manufacturing operation other than suitable finishing procedures as may be generally known to those skilled in these arts.

It is evident, therefore, that the manufacture of a step bar according to the present invention is a three-step procedure including extruding the basic shape, punching relieved portions in the upper edge of the longitudinally extending strips to form prongs and, finally, punching the base of the U-shaped structure to provide the openings 37 which permit the self cleaning function of the bar as well as to form transversely extending spacer bars 31.

It will be evident to those skilled in these arts that the structure of step bar according to the invention is unique because it comprises a monolithic structure requiring no intermediate securing, e. g. between the longitudinally extending strips and the transverse spacer bars, it requires no customized cutting to adapt it for use with particular ladder rails, and it is a structurally sound element capable of use in virtually every step bar application.

Although only a single preferred embodiment of step bar according to the invention is disclosed in detail, it is considered to be manifest that many modifications and variations to the basic teachings can be made without departing from the spirit thereof.

I claim:

1. A one piece safety step bar comprising a first longitudinally extending strip having an upper surface, a lower surface, a flat inner surface and an outer surface, said outer surface of said first longitudinally extending strip having a longitudinally extending portion of increased thickness adjacent its upper surface; 5
 a second longitudinally extending strip having an upper surface, a lower surface, a flat inner surface spaced from but disposed directly opposite said flat inner surface of said first longitudinally extending strip, and an outer surface, said outer surface of said second longitudinally extending strip having a longitudinally extending portion of increased thick-

10

ness adjacent its upper surface; a plurality of transversely extending spaced bars between said inner surfaces of said first and second longitudinally extending strips, said spaced bars being longitudinally displaced and disposed adjacent said lower surfaces of said first and second longitudinally extending strips; and a plurality of relieved portions formed in said upper surfaces of said first and second longitudinally extending strips, each said relieved portions being longitudinally from each adjacent relieved portion.
